CONVENIENCE OUTLET

Victor R. Despard, Syracuse, N. Y., assignor to
 Pass & Seymour, Inc., Syracuse, N. Y., a corporation of New York

Application April 21, 1932, Serial No. 606,733

12 Claims. (Cl. 177—311)

This invention relates to convenience outlets and particularly to the structure and mounting of contacts for such devices.

It is a general object of the present invention 5 to provide a novel and improved convenience outlet.

One of the important features of the invention resides in the provision of improved contact structure for use with convenience outlets.

10 Another important feature of the invention resides in the provision of a third or auxiliary contact for a two-pole convenience outlet adapted to be contacted by the same attachment plug blade as contacts one of the main terminals, whereby a circuit can be closed for lighting a pilot light.

15 A still further object of the invention resides in the provision of an auxiliary contact supported by but insulated from a portion of one of the main contacts and adapted to be engaged by the same plug blade as engages this main contact.

20 Other important features include the manner of mounting the contacts in the insulating housing, the terminal arrangement for the main and auxiliary contacts, and the closure means for the housing.

25 Other features and advantages of the invention will be more apparent to those skilled in the art upon a consideration of the accompanying drawing 30 and following specification, wherein is disclosed a single exemplary embodiment of the invention with the understanding that such changes and modifications may be made therein as fall within the scope of the appended claims without departing 35 from the spirit of the invention.

In said drawing:

Figure 1 is a side elevation of a convenience outlet constructed according to the present invention and shown mounted behind a cover or 40 wall plate which is in section;

Figure 2 is a longitudinal central section through the device of Figure 1;

Figure 3 is a fragmentary transverse section taken on line 3—3 of Figure 2;

45 Figure 4 is a vertical section taken on line 4—4 of Figure 2;

Figure 5 is a central vertical section through a terminal contact assembly taken on line 5—5 of Figure 3, omitting the housing and showing a plug blade in position to illustrate its engagement with both the main and auxiliary contacts;

Figure 6 is a perspective view of a main contact and its auxiliary contact; and

55 Figure 7 is a face view of a modified form of

convenience outlet for use with radio antenna and ground wires.

Convenience outlets are largely used both for supplying power for lamps and similar small portable devices, and also for supplying power for toasters, electric irons, and the like, where the power consumption is considerable and where there is danger of overheating resulting in fire if the devices are left connected too long and unattended. There has thus arisen a demand for 5 convenience receptacles which provide means for lighting a pilot lamp or similar warning signal to indicate that they are in use. The pilot light may be mounted in the same wall plate or may be mounted at a distance therefrom, as, for instance, in the kitchen to indicate that a power outlet in the cellar laundry is being used.

The present invention provides a convenience outlet which by the mere interchange of terminals can be made either a straight power outlet or a power outlet with provision for pilot light 10 operation and wherein contact assemblies are interchangeable with a convenience outlet intended for radio purposes and so polarized that 15 it is impossible to insert the wrong plug.

The invention is disclosed in connection with a 20 mounting bridge for supporting interchangeably a plurality of wiring devices, such, for instance, as shown in my application Serial Number 554,323, for Electric wiring apparatus. The 25 mounting bridge for supporting the convenience outlet in a conduit box is shown at 10 and the conventional cover or wall plate through which the face of the outlet extends is shown at 11. It will be appreciated that the invention is not 30 restricted to the particular way of mounting the convenience outlet but that it can be applied to conventional forms of single or duplex convenience outlets with equal facility.

The convenience outlet includes the body 12 35 of suitable insulating material, for instance, a molded composition, having a reduced neck portion 14 which projects through the opening in the cover plate. The casing or housing 12 is substantially rectangular in cross section, having the 40 end walls 15, the side walls 16, and the open back 45 which permits access to the recess 18 therein. This recess is associated with the front face by means of the attachment plug blade apertures 19.

Within the housing and inserted from the rear 50 is a pair of contact assemblies 20, 21. The assembly 20 is a single contact, whereas the assembly 21 includes both the power contact and an auxiliary contact for pilot light operation. These contact assemblies are interchangeable, 55

and it is possible to form a plain power outlet by providing two of the assemblies 20.

With the arrangement shown in Figure 2, one of each kind of the contact assemblies is included 5 to provide a pilot light operating power outlet. The main portions of the contact assemblies 20 and 21 are identical. Each is formed from a sheet of suitable resilient material, such as phosphor bronze, and includes a flat base 23 having 10 lateral lugs 24 thereon. Extending upwardly at right angles from this base 23 is the arm 25 offset as at 26 to provide a plug blade engaging portion 28 beyond which is a flared end 27 to guide the plug blade. The other arm of the generally U-shaped contact includes the wire terminal portion 29 which is perforated and threaded as at 30 for the reception of a terminal screw 31. It is 15 thence offset as at 32 to bring the blade engaging portion 33 close to the portion for the same purpose on the opposite arm. It also is provided with a flared end 34. The plug blade 35 is received between the two spring arms of the contact and electrically engages both of them.

The contact assembly is mounted in the housing by being dropped into position through the rear opening in the housing and with the lugs 37 on the terminal portion 29 seated in grooves 38 at the junction of the sides and end wall of the housing. The lugs 24 on the base of the 20 contact assembly are received in notches 39 in the rear edges of the side walls. Thus the terminal is prevented from moving in the direction of the axis of the terminal screw and also from rotating about an axis through the lugs 24, since 25 a portion of the terminal section engages the end wall as at 40. When in position, the flared ends 27 and 34 of the contact arms straddle the opening 19 and clear the back of the front wall to permit freedom of movement.

40 The lugs 24 are set into the notches 39 at such a depth that the bottom wall of the base 23 of the contact is flush with the rear edges of the side and end walls of the housing, and the housing end is then closed by an insulating sheet 42 held 45 in position by a metal plate 43 partially covering it and having the down turned lugs 44 received in shallow recesses 45 in the side walls of the housing and secured therein in any suitable manner, as, for instance, in accordance with the showing 50 in my copending application Serial Number 587,599, for Attaching means for metal parts and insulating material. The terminal screws 31 have their heads and a portion of the part 29 of the contact assembly adjacent them exposed through 55 the notches 46 at the rear edges of the end walls in order that wires may be attached thereto.

To support an auxiliary contact which is adapted to be connected electrically to the main contact by a plug blade to place a pilot light in 60 circuit, it is found convenient, according to the present invention, to support this auxiliary contact from one arm of a main contact. For this purpose the arm 25 of the main contact is provided with a rectangular aperture 50, best seen in Figures 4 and 5. Disposed laterally of this aperture on the edges of the arm is a pair of integral lugs 51 bent up at right angles to the plane of the arm. A sheet of insulating material 52 is applied against the outer face of the arm 25 between the base and the offset 26, and is notched 65 as at 53 to receive the lugs 51 which are then split and spread as at 54 to securely hold the sheet in place.

The sheet is centered over the aperture 50 and 70 is centrally perforated as at 56 for the passage

5 of the shank 57 of the auxiliary contact which is formed from a sheet of metal to have a substantially semi-circular head 58 which overhangs the shank sufficiently so that, when inserted through the aperture 56, the overhang rests against the inner face of the insulation sheet and the head clears the aperture in the arm of the main contact. After being positioned, the shank is split and spread as at 59 to permanently secure the auxiliary contact in position. Of course the auxiliary contact is engaged in the insulation sheet before this sheet is mounted on the main terminal. As seen in Figure 5, the blade 35 of the attachment plug passes up between the arms of the main contact, engages both of them and has its inner end in contact with the rounded face of the auxiliary contact.

To provide a connection to this auxiliary contact, it is found convenient to provide a hole 60 in the end of the shank and to pass the tinned end 61 of an insulated flexible conductor 62 through this hole and to then stake the hole closed as clearly seen in Figures 2 and 5. This pinches the wiring in position, making a secure mechanical connection and a suitable electrical connection. 20 The conductor 62 is led out through a close fitting hole 63 in the insulation sheet 42 and through a larger hole 64 in the metal cover plate 43.

The main terminals are made exactly alike for 25 convenience in manufacture and only those requiring the auxiliary terminal have the insulation sheet carrying this terminal applied thereto. The others have the aperture and the lugs 51 which are not used.

In the event that a convenience outlet is desired for radio purposes to make connection between the set and the antenna and ground, the 30 convenience outlet of the present type may be slightly modified as shown in Figure 7 to adapt it for this purpose. The modification consists in 35 inclining one of the plug blade receiving apertures 72 at an angle of about 22½° with the longitudinal axis of the other recess. This makes only the slight variation in the face seen in Figure 7, but the main portion of the body must be 40 enlarged as at 70 in order to receive a contact assembly identical with that shown at 20 in Figure 2 but inclined at the same angle as the aperture 72 in order that a blade passing through that aperture will directly engage it. Such a convenience outlet will be provided with two plain contact assemblies which are positioned and held in place exactly as described in connection with the power outlet embodiment.

Having thus described the invention, what is 55 claimed as new and desired to be secured by Letters Patent is:

1. In a convenience outlet, in combination, a pair of contact springs for connection to a power circuit and arranged to be contacted by the 60 prongs of an attachment plug, a contact for connection to a pilot lamp and insulating means attached to one of said contact springs and supporting said contact therefrom and in the path of the plug prong engaging said spring for contact therewith.

2. A contact assembly for a convenience outlet including in combination, a spring member having a pair of arms spaced to receive and electrically contact a plug blade therebetween, insulating material secured to one of said arms and an auxiliary contact member carried by said material and disposed between said arms in the path 70 of the plug blade for contact therewith.

3. A contact member for a convenience outlet 75

- including in combination, a sheet of metal formed into U shape to receive a plug blade between the arms thereof, one of said arms having an aperture, a contact element extending through said aperture out of contact therewith and having a portion in the path of and to engage the plug blade when inserted between the arms, and insulating material supporting said element from one of said arms. 5
10. 4. A contact member for a convenience outlet including in combination, a resilient contact arm having a portion offset to be engaged by a plug blade, said arm having an aperture therein below said offset, an auxiliary contact extending through said aperture and into the path of said blade to be engaged thereby, and insulating material supporting said auxiliary contact from said contact arm. 10
15. 5. A contact member for a convenience outlet including in combination, a resilient contact arm having a portion adapted to be engaged by a plug blade, an auxiliary contact and insulating material supporting said auxiliary contact from said contact arm and in the path of the plug blade to be engaged thereby. 20
25. 6. A contact member for a convenience outlet including in combination, a contact arm of sheet metal having an aperture therein, a lug extending from each of the lateral edges of the arm and bent at right angles to the plane thereof, a sheet of insulation against one face of said arm and secured thereto by said lugs, and an auxiliary contact carried by said sheet and extending through said aperture to a position to be engaged by the same plug blade which engages the main contact member. 30
35. 7. A contact member for a convenience outlet including in combination, a contact arm of sheet metal having an aperture therein, a lug extending from each of the lateral edges of the arm and bent at right angles to the plane thereof, a sheet of insulation against one face of said arm and secured thereto by said lugs, said sheet having an aperture smaller than and registering with the aperture in said arm and an auxiliary contact extending through both apertures, said auxiliary contact being out of electrical engagement with the arm and extending to a position to be engaged by the same plug blade which engages the main contact member. 40
45. 8. A contact member for a convenience outlet including in combination, a contact arm of sheet metal having an aperture therein, an auxiliary contact at one face of said arm and having a portion extending through the aperture, insulation supporting said auxiliary contact from said arm and out of engagement therewith, a wire receiving terminal means for said arm and a terminal for said auxiliary contact on the opposite side of said arm from the auxiliary contact, said main and auxiliary contacts being positioned to be engaged by the same plug blade. 5
50. 9. In a convenience outlet, in combination, a housing of insulating material having plug blade receiving openings in its front face and an open back, a pair of contact springs inserted from the back, a terminal member on each contact spring and extending through an end wall of the housing, an auxiliary contact adapted to be electrically connected to one of the contact springs by a plug blade, and a connecting member for said auxiliary contact extending through the rear of said housing. 15
55. 10. In a two-pole convenience outlet, in combination, a pair of main contact members each adapted to be engaged by a blade of an attachment plug, a third contact and main contact supported insulating means positioning said third contact for engagement by the said plug blade that engages one of the main contact members. 20
60. 11. In a convenience outlet, in combination, a pair of contact springs for connection to a power circuit and each having a portion near one end adapted to be contacted by a blade of an attachment plug, a contact for connection to a pilot lamp, means insulating and supporting said contact from one of said contact springs, the relative positions of said portion and contact being such that the plug blade first engages the portion and then while still in contact therewith engages the contact. 25
65. 12. In a convenience outlet, in combination, a pair of contact springs for connection to a power circuit and each having spaced arms near one end adapted to contact two sides of a blade of an attachment plug, a contact for connection to a pilot lamp, means supporting said contact between one pair of said arms and out of engagement with the springs, the said contact being so located that it is engaged by a plug blade after that blade has engaged the adjacent contact 30
70. spring arms. 35
75. 80. 85. 90. 95. 100. 105. 110. 115. 120. 125. 130. 135. 140. 145. 150. 155. 160. 165. 170. 175. 180. 185. 190. 195. 200. 205. 210. 215. 220. 225. 230. 235. 240. 245. 250. 255. 260. 265. 270. 275.
